WALDO E. ROSEBUSH, OF SPOKANE, WASHINGTON, ASSIGNOR TO INLAND EMPIRE PAPER CO., OF MILLWOOD, WASHINGTON, A CORPORATION OF WASHINGTON.

GRINDSTONE MOUNTING.

1,405,335.

Specification of Letters Patent. Patented Jan. 31, 1922.

Application filed April 6, 1921. Serial No. 458,937.

To all whom it may concern:

Be it known that I, WALDO E. ROSEBUSH, a citizen of the United States, and a resident of Spokane, in the county of Spokane and 5 State of Washington, have invented a new and Improved Grindstone Mounting, of which the following is a full, clear, and exact description.

The object of the invention is to provide 10 a new and improved mounting for grindstones such as are used for pulp mills and other establishments and arranged to securely hold the grindstone in position on the shaft or spindle and to allow of conveniently and quickly releasing and removing 15 a worn out grindstone and replacing the same by a new one.

Another object is to permit of removing a worn out grindstone without breaking it up 20 while held in the mounting.

Another object is to permit of readily reusing a worn out large grindstone of one pulp mill in a pulp mill requiring a stone of less diameter.

25 Another object is to provide a mounting which is very simple and durable in construction and not liable to get easily out of order.

With these and other objects in view, the 30 invention consists of certain novel features of construction as hereinafter shown and described and then specifically pointed out in the claims.

A practical embodiment of the invention 35 is represented in the accompanying drawings forming a part of this specification, in which similar characters of reference indicate corresponding parts in both views.

Figure 1 is a front elevation of the improved 40 grindstone mounting with parts shown in section; and

Figure 2 is a side elevation of the same with the shaft or spindle shown in section.

The shaft or spindle 10 is provided with 45 right and left hand screw threads 11 and 12 on which screw bushings 13 and 14 carrying removable dished flanges 15 and 16 bearing against the sides of the grindstone 17 to be held in position on the shaft or spindle 10.

50 Each of the flanges 15 and 16 is removably fitted on the corresponding bushing 13 or 14 and rotates with the same, preferably by the use of a key 20. Each of the bushings 13 and 14 is preferably made in two or more parts to permit of readily placing the bush-

ing in position on the screw threads 11 and 12 or to remove the same therefrom after the corresponding flange 15 or 16 has been removed from the bushing.

Either or both of the bushings 13 and 14 are provided with an annular groove 21 into which fits a collar or a ring 22 made in sections having lugs 23 fastened together by bolts 24. The collar or ring 22 projects a sufficient distance beyond the peripheral face 65 of the corresponding bushing 13 or 14 to provide an abutment for the outer face of the corresponding flange 15 or 16. Thus the flange 15 is supported on the corresponding bushing 13 or 14 and is held against the 70 grindstone by the collar or ring 22 on screwing up the corresponding bushing 13 or 14.

When it is desired to remove the grindstone 17 it is only necessary to remove the bolts 24 to allow of removing the corresponding 75 collar or ring 22 thus releasing the flanges 15 or 16 of its outward strain. The bushing 13 or 14 can now be readily unscrewed from the screw threads 11 or 12 and removed from the shaft, but in case the 80 bushing does not unscrew easily it is only necessary to remove the key 20 to allow of sliding the flange off the bushing endwise. The bushing being in two or more parts can now be readily pried off the corresponding 85 screw thread 11 or 12 to release the grindstone 17 and allow its removal from the shaft or spindle 10.

From the foregoing it will be seen that by the arrangement described the grindstone 90 is securely held in position on the shaft or spindle 10, and this grindstone after being worn can be readily removed and replaced by a new one without requiring breaking up 95 of the stone and allowing the use of such removed stone in a pulp mill requiring a grindstone of smaller diameter.

Having thus described my invention, I claim as new and desire to secure by Letters Patent:

1. A grindstone mounting comprising a flange adapted to engage one side of the grindstone, a sectional bushing on which the said flange is removably mounted, and means removably mounted on the said bushing for 100 clamping the sections thereof together and against which butts the outer side of the said flange.

2. A grindstone mounting comprising a flange, a sectional bushing removably carry- 110

ing the said flange and held on the grindstone shaft, the said bushing having a peripheral groove adjacent the flange, and a sectional collar held in the said groove and 5 against which butts the outer side of the said flange.

3. A grindstone mounting comprising a shaft having a threaded portion, a sectional

bushing screwing on the said threaded shaft portion and having an annular groove, a 10 flange removably fitting on the said bushing, a key connecting the bushing with the flange, and a sectional retaining collar fitting into the said groove and against which butts the outer side of the said flange.

WALDO E. ROSEBUSH.
